UNITED STATES PATENT OFFICE.

G. V. SHEFFIELD AND J. F. COBURN, OF HOPKINTON, MASSACHUSETTS.

IMPROVED MACHINE FOR PIERCING LEATHER.

Specification forming part of Letters Patent No. 57,780, dated September 4, 1866.

To all whom it may concern:

Be it known that we, GEORGE V. SHEFFIELD and JAMES F. COBURN, of Hopkinton, in the county of Middlesex and State of Massachusetts, have invented a new and Improved Machine for the Piercing of and Inserting Steel or other Wires in Leather; and we do hereby declare that the following is a full, clear, and exact description thereof, which will enable others skilled in the art to make and use the same, reference being had to the accompanying drawings, forming part of this specification.

The present invention relates to a machine to be used for the piercing of leather and inserting steel or other wires therein, the object being to increase the wear and durability of the leather; and the invention consists in a novel arrangement of mechanical devices, whereby the leather is fed through the machine, first to the piercing instrument or tool, and then to the die for forcing the wire therein, which tool or die is brought to bear at the proper times against the leather, as will be apparent from the following detail description of the machine, reference being had to the accompanying plate of drawings, in which—

Figure 1 is a front elevation of the machine; Fig. 2, an end elevation; Fig. 3, a transverse vertical section, taken in the plane of the line $x x$, Fig. 1; Fig. 4, a detail view to be herein-after referred to.

Similar letters of reference indicate like parts.

A in the drawings represents the bed of the machine, having at each end an upright post, B. Across from one to the other extends an arch beam or bar, C, secured to the same at each end in any proper manner; D, the driving-shaft, turning at one end in bearings of one of the upright posts B, and extending horizontally under the arch-beam C for about one-half of its length, and turning in bearings of the hanger E, secured to the under side of the beam C; F, a pulley, secured to driving or main shaft D, around which it is intended to pass an endless belt or band, for the driving of the same. The shaft D has two cams, G and H, secured to it, one, G, between the pulley and end post, and the other, H, at the inner end of the shaft; I, a horizontal platform or table, secured in and between the two uprights B B, under which table, in the direction

of its length, extends a horizontal shaft, J, turning in bearings at each end of the posts B, and with a ratchet-wheel, K, secured to one of its ends upon the outside of the post, between which and the pulley of the main shaft the cam G is placed; L, an upright lever-arm, hung and turning by its forked end M upon the shaft J as a fulcrum, in which lever is hung a spring-pawl, N, engaging with the teeth of the ratchet K, through which pawl, as the lever is swung forward by the abutment against, and travel of, the cam G over its upper end, the ratchet-wheel, and consequently its shaft J, are revolved, when, the cam releasing itself from the lever, it is drawn or swung back to its original position by means of a spiral spring, O, hung at one end to it and at the other connected with a fixed staple, P, of the end post, B, the spring-pawl Q, hung upon the post and engaging with the ratchet-wheel K, preventing it from being turned in the opposite or wrong direction.

At a point half-way, or nearly so, between the two end posts B B, a feed-wheel, R, is secured to the shaft J, the edge or periphery of which is roughened, and projects slightly above and through the central opening, S, in the platform or table.

T is a bar placed just above the table I, and parallel with it, extending from one post, B, to the other.

V is a slide, moving in and between the uprights V V upon the upper side of the horizontal bar T, the upper end of which slide is hung upon a lever-bar, W, extending toward one of the posts B under the main shaft D, turning upon a fulcrum, a, of such post. In the lower end of this slide the tool X, for piercing the leather, and the hammer-rod J, for forcing the wire into the hole pierced by the tool X, are secured, the latter to the rear of the former, but in the same line therewith, as plainly shown in the drawings, (see Fig. 3,) both of which tools play through suitable apertures made in the block Z, secured to the under side of the bar T. A² is a bent spring, secured to the upper side of bar T, and so bent around that the lever W rests upon it.

B² is another lever-bar similarly hung to the same post with the lever W, and extending therefrom in a line parallel with said lever, but to the rear of it, with a slide, C², hung

upon its outer end and moving in and between the guide-uprights D² of the bar T. On this slide is a spring-pawl, E², that, as the slide is depressed, engages with the teeth b of the ratchet feed rollers or wheels F², placed with their peripheries in contact, or nearly so, with each other. These rollers are hung within the bar T, so as to move toward or away from each other, and are held so as to tightly bind the wire which passes in and between them by means of rollers or wheels G², one to each wheel F², upon their outside edges, hung in the lower end of lever-arms H², turning upon fulcrums of the bar T, the upper ends of which arms are connected together by a spiral spring, I². J² is a bent spring, secured to upper side of bar T, on which spring the lever B² rests.

K² is a knife or chisel, secured in inner end of a horizontal slide, L², arranged in the under side of bar T, the outer end of which slide is connected to the arm M² of a shaft, N², turning at each end in bearings of the projecting pieces upon the rear side of the bar T, which shaft has a long projecting arm, P², extending upward toward the cam H, against which the cam acts as it is revolved, moving in the said slide with its chisel, which is drawn out when the cam has become free of the said arm P² by the action of the spiral spring Q² coiled around the said shaft N².

Having thus in detail described the various parts composing the machine embraced in the present invention, I will now proceed to explain the manner in which they operate.

The leather which is to be pierced with wire is placed upon the platform I over the feed-roller R, against which it is held in close contact by the projecting block Z of the bar T, when, turning the main or driving shaft D in any proper manner, and in the right direction, the leather is caused to be fed along through the action of the pawl N, upon the ratchet-wheel K of the feed-shaft J, when the cam H then acting upon the lever W, the slide U,

with the piercing tool and hammer, is forced down and toward the leather, causing the piercing-tool to pierce the same, and the hammer to force in the hole previously pierced the wire which is intended to insert therein, that by the action of the cam upon the next lever B² is fed downward, and broken or cut off by the chisel or knife K², and at the same time thrown into proper position for the hammer to act upon and force it into the leather, the above-described operation of the machine continuing so long as the driving or main shaft is turned.

The feed-rollers F² for the wire are grooved, so as to guide the wire between them, and cause a better and firmer hold upon it.

To enable the feed-roller R to be adjusted in height with reference to the platform S, we have arranged the journals or boxes F² of its shaft J in ways or guides G² of the frame-work uprights B B, in the lower side of each of which boxes F² screws a spindle, H², having a bevel-gear wheel, I², upon their lower ends, which are connected together through bevel-gear wheels J² upon the horizontal shaft K², having a milled flange or wheel, L², for convenience in turning it, whereby, as is obvious, if the said shaft K² be turned the feed-roller shaft can be either raised or lowered, as the case may be, in an even manner throughout its whole length.

We claim as new and desire to secure by Letters Patent—

The combined arrangement of the feed-wheel R, piercing-tool X, hammer Y, feed-rollers F², and sliding chisel R², or its equivalent, substantially as herein described, and as and for the purpose specified.

GEORGE V. SHEFFIELD.
JAMES F. COBURN.
